(57) **CLAIM**

The ornamental design for an adjustable food preparation device, as shown and described.

DESCRIPTION

FIG. 1 depicts a perspective view of an adjustable food preparation device in accordance with an exemplary embodiment of the present invention showing an underside of the adjustable food preparation device;

FIG. 2 depicts a second perspective view of the adjustable food preparation device in accordance with an exemplary embodiment of the present invention showing a top view of the adjustable food preparation device;

FIG. 3 depicts a front side view of the adjustable food preparation device in a standing position in accordance with an exemplary embodiment of the present invention;

FIG. 4 depicts a rear side view of the adjustable food preparation device in a standing position in accordance with an exemplary embodiment of the present invention;

FIG. 5 depicts a first side view of the adjustable food preparation device in a standing position in accordance with an exemplary embodiment of the present invention;

FIG. 6 depicts a second side view of the adjustable food preparation device in a standing position in accordance with an exemplary embodiment of the present invention;

FIG. 7 depicts a top view of the adjustable food preparation device in accordance with an exemplary embodiment of the present invention showing a top surface.

FIG. 8 depicts a bottom view of the adjustable food preparation device in accordance with an exemplary embodiment of the present invention where each leg is extended; and, FIG. 9 depicts a second bottom view of the adjustable food preparation device in accordance with an exemplary embodiment of the present invention where each leg is folded.

The broken lines shown in the drawings are for illustrative purposes only and form no part of the claimed design.
